UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

PUSH-BUTTON.

1,143,207.

Specification of Letters Patent. Patented June 15, 1915.

Application filed August 3, 1912. Serial No. 713,049.

To all whom it may concern:

Be it known that I, CHARLES J. KLEIN, a citizen of the United States, residing at Milwaukee, in the county of Milwaukee and 5 State of Wisconsin, have invented new and useful Improvements in Push-Buttons, of which the following is a full, clear, concise, and exact description, reference being had to the accompanying drawing, forming a 10 part of this specification.

My invention relates to push buttons.

It has among its objects to provide improved means for elongating a push button of an electric switch. Other objects and 15 advantages of my invention will hereinafter appear.

In order that my invention may be clearly and fully disclosed, I have illustrated several embodiments of the same in the accompanying drawing. It is to be understood, however, that the forms herein illustrated 20 are susceptible of modification.

Figure 1 shows a push button operated switch mechanism in position in a fixture 25 and equipped with one form of my invention. Fig. 2 shows a detailed view of a push button with an extension thereon, the extension being shown in section. Fig. 3 shows a modified form of the construction 30 shown in Fig. 2. Fig. 4 illustrates a further modified form.

The push buttons 1 of the switch mechanism are provided with cylindrical caps or extensions 2, having open ends, which are 35 adapted to be slipped over the ends of the push buttons and attached thereto.

In the construction shown in Figs. 1, 2 and 3, the open ends of the caps are slotted as at 3, and provided with sliding bands 40 or rings 4 of slightly larger diameter than the diameter of the exterior of the cap. By adjusting these bands longitudinally of the cap, the extensions are readily attached to or removed from the push buttons. In 45 order to prevent the cap from being slipped too far over the end of the push button and to provide a substantial means for taking up the thrust applied to the end of the cap without leaving the strain upon the holding 50 band 1, I provide the cap with an annular internal bead or flange 5, which, when the cap is in position upon the end of the push button, abuts against the end of the latter.

In applying the extension or cap to a 55 push button, the open end of the same is

slipped over the end of the push button. The cap is then locked and securely held upon the push button by sliding the band 4 along the same to the position shown in Fig. 1. Obviously a cap may be made of any desired length in order to adapt it to use in any desired relation. When it is desired to remove the cap, all that it is necessary to do is to slide the band or ring in the opposite direction and then withdraw the cap.

In order that the caps or extensions may at the same time serve as means for indicating the position of the switch mechanism, I provide the caps with certain distinguishing means. For instance, I may provide one of the push buttons with a white cap or extension, while the other push button may be provided with a black cap.

Fig. 2 shows a cap formed of sheet metal and having a countersink 6 in its end, in which is set a disk or filling 7 of pearl, enamel or other suitable material adapted to serve as an indicator. By so distinguishing the cap I am able to make the same serve as visual indicators by which a person at a glance may determine the condition of the switch.

Fig. 3 shows a modified form of the construction shown in Fig. 2. In this form the end of the push button is provided with an annular groove 8 adapted to receive a correspondingly shaped annular flange or bead 9 upon the periphery of the cap. As in the construction heretofore described, the cap may be secured to the push button by means of the sliding ring or band.

Fig. 4 shows a further modified form of cap wherein the end 10 of the cap is threaded and carried upon a correspondingly threaded portion of the push button, which, if desired, may be made of reduced cross section. Obviously by adjusting the cap upon the threaded end of the button the length of the extension may be varied as desired.

By the use of my invention I am able to materially increase the range of usefulness of push button devices. For instance, push button switches having push buttons of standard lengths may be readily adapted to use in large casings by simply attaching extensions to the ends of the same. These extensions may obviously be made of any suitable material and thus adapted to a wide range of uses.

While I have in this application described several forms of my invention in order to disclose the same, I do not restrict myself to the forms herein shown for purposes of illustration.

5 What I claim as new and desire to secure by Letters Patent of the United States is as follows:—

1: In combination, a push button, a cylindrical extension cap having a longitudinally slotted end inclosing the end of said push button, said cap having interior projections abutting against a shoulder on said button, and a sliding ring carried by said cap for 15 compressing the slotted end thereof upon the end of said button.

2. In combination, a push button having an annular groove therein, a cylindrical extension cap having a longitudinally slotted end inclosing the end of said push button, 20 said cap having interior projections fitting in said groove, and a sliding ring carried by said cap for compressing the slotted end thereof upon the end of said button.

In witness whereof, I have hereunto subscribed my name in the presence of two witnesses.

CHARLES J. KLEIN.
